Primary Examiner — R. Johnson(74) Attorney, Agent, or Firm — Ying-Ting Chen; Law Office of Michael Chen(57) CLAIM

The ornamental design for a detachable silicone piano sticker, as shown and described.

DESCRIPTION

FIG. 1 is the front, right, top perspective view of a detachable silicone piano sticker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of the portion taken at line-8 in FIG. 1.

The broken lines represent the portions of the detachable silicone piano sticker that form no part of the claimed design.
